UNITED STATES PATENT OFFICE.

JOHN CARPENTER, OF NORTH AUCKLAND, NEW ZEALAND.

PROPELLER.

Application filed July 22, 1918. Serial No. 246,243.

To all whom it may concern:

Be it known that I, JOHN CARPENTER, a citizen of New Zealand, residing at North Auckland, New Zealand, have invented new 5 and useful Improvements in Propellers, of which the following is a specification.

This invention relates to screw propellers and it has for its object to produce a propeller of simple and improved construction, 10 the blades or flukes of which have bearing faces of great area, whereby the operation of the device will be rendered particularly effective.

A further object of the invention is to 15 produce a screw propeller, the blades or flukes of which are spirally disposed with respect to the hub or axis of rotation, said blades or flukes extending at each end uninterruptedly beyond the corresponding end 20 of the hub, thereby increasing the effective operating area of the blades.

With these and other ends in view which 25 will readily appear as the nature of the invention is better understood, the same consists in the improved construction and novel arrangement and combination of parts which will be hereinafter fully described and particularly pointed out in the claim.

In the accompanying drawing has been 30 illustrated a simple and preferred form of the invention, it being, however, understood that no limitation is necessarily made to the precise structural details therein exhibited, but that changes, alterations and 35 modifications within the scope of the claim may be resorted to when desired.

In the drawing,—

Figure 1 is a side view of a propeller constructed in accordance with the invention.

40 Figure 2 is an end view of the same.

Figure 3 is a transverse sectional view taken on the line 3—3 in Figure 1.

Corresponding parts in the several figures are denoted by like characters of reference.

45 The improved propeller includes a longitudinal central portion 15 which constitutes a hub, said central portion having a bore 16 formed longitudinally thereon, and transverse threaded openings 17 being also pro-

vided for the reception of fastening members, such as screws 18, whereby the device may be securely mounted on a revoluble shaft 19.

Formed on opposite sides of the hub 15 are blades or flukes 20 which are spirally disposed, each of said blades making a half spiral convolution with respect to the hub. Each of the blades or flukes is of a length materially exceeding the length of the hub, said blades having rounded end portions 21 60 which extend uninterruptedly beyond the ends of the hub, thereby materially increasing the effective area of the blades.

In the construction of the improved propeller it will be noted that the same is preferably formed of single casting, and that the diameter of the hub does not exceed the thickness of the blades or flukes at the juncture of said blades or flukes with the hubs, the blades or flukes being tapered from 70 the hub and outwardly to a thickness which will not exceed that which is necessary to produce the requisite strength. The result of this construction will be that the spiral grooves or convolutions formed by the respective blades or flukes will be smooth and uninterrupted throughout and free from any projections that would be liable to form any resistance to the operation of the device.

From the foregoing description taken in 80 connection with the drawing it will be readily understood that the improved propeller may be readily applied to the propulsion of any floating craft, and that the operation thereof will be equally effective without regard to the direction of rotation.

What is claimed is:—

A propeller comprising an elongated hub portion, and a pair of spiral blades projecting from opposite sides thereof and correspondingly arranged, the ends of the blades projecting materially beyond the ends of the hub portion with all the extremities of the blades being semi-circular in shape.

In testimony whereof I affix my signature.

JOHN CARPENTER.
